MACHINE FOR CUTTING SKINS

Robert H. Konikoff, New York, N. Y., assignor to Jess Cohen, Louis Passloff, Olga Schneebalg, and Doris Weinberg, New York, N. Y., copartners, doing business under the firm name of American Lambskin Products

Application March 6, 1944, Serial No. 525,295

1 Claim. (Cl. 164—60)

This invention relates to new and useful improvements in means for cutting furred skins, and has for its principal object the provision of a novel apparatus and method of cutting circular discs from the skins without cutting or otherwise damaging the fur.

The apparatus and method of the present invention may be used for cutting any type of furred skins, and it is particularly effective for cutting circular discs from lamb skins for use as powder puffs, or the like. Heretofore, the cutting of such articles has been accomplished either by the use of a simple fur-cutting knife, or by the use of an appropriately-shaped cutting die. When the cutting die is used, the skin is placed, fur side down, on any suitable support, such as an end grain wooden block, and the cutting die placed on the upper or skin side, and the die then struck with a hammer.

The objection to this method resides in the fact that the die cuts the hairs as well as the skin, and since the hairs are disposed in one direction and are lying flat during the cutting operation, there is a considerable waste occasioned by the cutting of the hairs lying under the annular cutting edge. In the event that such hairs were not severed, and the hairs on the disc thereafter brushed out in the usual manner, the resulting powder puff has a considerably larger diameter than the diameter of the skin disc. Accordingly, it has been a more accepted practice to cut these discs with an ordinary fur cutter's knife, taking care to cut only through the skin, and not through the fur. This latter method, however, is slow and tedious, and any saving in material is offset by a substantial increase in labor charge.

It is an object of the present invention to provide a high-speed cutting tool which will cut through the skin portion only, and thus leave the hairs below the skin uncut, and accordingly make for a considerable saving in material. Another object of the present invention is to provide a high-speed cutting device of this general character which is efficient in operation, and which can be operated by one possessing only a moderate amount of skill.

The method of the present invention consists essentially in supporting the skin, fur side down, on a generally horizontal supporting surface, and then moving a rotating annular cutting element downwardly into contact with the skin, the cutting element rotating at sufficiently high speed to cut through the skin without the necessity of compressing the fur between the cutting element and the work support. In this fashion, the skin

may be cut without the cutting element entering the furred section, thus avoiding severing of the hairs by the cutting element.

Other objects and advantages of the invention 5 will be hereinafter pointed out, or will become apparent, as the specification proceeds.

In the drawing:

Fig. 1 is a side elevation of a machine forming one embodiment of the present invention.

10 Fig. 2 is a broken horizontal section taken on line 2—2 of Fig. 1.

Fig. 3 is an enlarged detailed view of the cutting element and showing the manner in which the skin is cut without cutting the hairs.

15 Fig. 4 is a section taken through a disc cut by the machine and method of the present invention after the hairs have been brushed out.

Fig. 5 is a section taken through the ordinary fur-cutting die of the type previously referred to.

20 Fig. 6 is a section taken through a disc cut by such die.

The cutting element 10 of the present invention is shown in some detail in Fig. 3, and comprises a circular portion having a depending annular 25 flange 11. At its lower end, this flange is bevelled on its outer surface, as shown at 12, thus forming an annular cutting edge 13. The inner surface of the flange 11 is straight, as shown at 14. The circular portion 10 is carried by, or is formed integrally with, a shank 15, which may be mounted in some appropriate chuck 16 carried on motor shaft 17 of a motor 18. The motor is suitably, and preferably removably, supported in motor carriage 19, which may include a plurality 30 of annular strap elements 20. Motor support 19 has oppositely-disposed vertical flanges 24 which are received in frame elements 25 and 26 forming trackways, thus providing means for longitudinal 35 up-and-down movement of motor carriage 19 and motor 18.

Frame elements 25 and 26 are part of a general frame structure 30, which may include vertical members 31 and 32, as well as a horizontal work 40 support 33. Downward movement of motor carriage 19 is controlled by means of a foot treadle 37 journaled at 38 in frame 30. Downward movement of the foot treadle 37 causes downward movement of a link 39, the upper end of which is appropriately connected at 40 to a pair of endless chains 41, which are supported by sprockets 42 and 43 at the lower and upper ends thereof, respectively.

45 The following means are provided for connecting the chains with the motor carriage 19, shown 50 particularly in Fig. 2. A rearward extension 47

on the motor carriage supports a cross-bar 48, which is secured thereto by means of screws 49, the chains 41 being clamped between elements 48 and 47. It will accordingly be seen that when the foot treadle 37 is depressed, chains 41 draw the motor carriage, the motor, and the cutting element 10 downwardly, and when pressure on the foot treadle is released, the chains are caused to move in the opposite direction, and the motor carriage accordingly raised, by means of a coil spring 52 which is secured at its upper end at 53 to the chains 41, and at its lower end at 54 to a horizontal frame member 55. Suitable adjustable stop means limiting downward movement of the motor carriage may also be provided.

The method of operating the machine is shown in Fig. 3, wherein the skin 60, having the fur 61 on one side thereof, is placed, fur down, on the horizontal work support 33. Cutting element 10 with annular cutting edge 13 is now lowered to a point where the cutting edge contacts the skin and cuts through such skin, but not through the fur. The speed of rotation of the cutting element is an important aspect of the present invention, since superior results are achieved only by providing a relatively high-speed motor of the order of 3600 R. P. M. This assures a cleaner cut, and results are otherwise far more satisfactory, than would be the case if the motor operated at a considerably lower speed.

As the cutting edge 13 descends and commences its operation of cutting through the skin, the skin will, of course, be depressed, but only slightly, and the stop means limiting downward movement of the cutting element are so arranged as to permit the cutting element to cut completely through the skin, but not through the fur. It will be noted from Fig. 3 that the individual hairs 61 are not perpendicular with the surface of the skin, but rather are disposed in one direction, which is the case in practically all furred skins.

For certain types of skins, it may be desirable to provide means for holding the disc while the same is being cut, thus preventing the cut disc from remaining within the recess of the cutting element, which occasionally occurs in light-weight skins. These means may include an opening 62 in the center of the cutting member, which opening receives a headed pin or button 63 which engages the center of the disc. This button is readily removable. The fur on the resulting disc 65 is then brushed in all directions, thus causing the

5 hairs 66 to project radially from the center of the disc. In this fashion, the over-all diameter of the furred surface is from 20% to 30% greater than the diameter of the fur disc itself, thus achieving a considerable saving in material.

The advantage of the method and apparatus of the present invention becomes more apparent when considered in contrast with the commonly practiced method shown in Figs. 5 and 6, wherein 10 70 represents the usual annular cutting die, having a cutting edge 71. As the disc 72 is cut, the skin and the fur are obviously compressed between the cutting edge 71 and the work support, and accordingly the cutting edge severs the individual hairs 73 lying immediately therebeneath, as well as the skin. This produces the result shown in Fig. 6, wherein the hairs 74 have been severed, and accordingly, when the hairs are 15 brushed out, they will extend from the marginal edge of the disc on the right side, when viewed as in Fig. 6, but not on the left side, which produces a distorted circle.

20 While I have herein shown and described one form or embodiment of my invention for illustrative purposes, and have disclosed and discussed in detail the construction and arrangement incidental to a specific application thereof, it is to be understood that the invention is limited neither to the mere details or relative arrangement of parts, nor to the specific embodiment shown herein, but that extensive deviations from the 25 illustrated form or embodiment of the invention may be made, without departing from the principles thereof.

30 What I claim is:

35 An apparatus for cutting circular discs from furred skins comprising a frame, a vertically-reciprocable support slidable in the frame, a foot treadle journaled adjacent the lower end of the frame, means connecting the support with the treadle to reciprocate the support, a motor with its shaft disposed vertically carried by the support, a cutting element formed with an annular cutting edge carried at the lower end of the motor shaft, and a work support carried by the frame for 40 receiving a furred skin, fur side down, on such support, whereby the annular cutting element may be moved downwardly, by depressing the foot treadle, into cutting relation relative to the skin while rotating at high speed to cut such circular discs from the skin.

45 ROBERT H. KONIKOFF.
